Primary Examiner—Celia Murphy**[57] CLAIM**

The ornamental design for a pair of shoe soles, as shown and described.

DESCRIPTION

FIG. 1 is a bottom plan view of the right component of a pair of shoe soles showing my new design, the left component being a mirror image thereof;

FIG. 2 is a right side elevational view thereof, the broken lines showing a shoe upper being for illustrative purposes only and forming no part of the claimed design;

FIG. 3 is a left side elevational view thereof;

FIG. 4 is a front elevational view thereof; and,

FIG. 5 is a rear elevational view thereof.

The portions left unshaded in FIGS. 3 through 5 represent unclaimed subject matter.
